TOOL-GUIDE

Herbert W. Thornburg and Irwin C. Smith, South Milwaukee, Wis., assignors to Bucyrus-Erie Company, South Milwaukee, Wis., a corporation of Delaware

Application March 13, 1953, Serial No. 342,149

7 Claims. (Cl. 255—5)

This invention relates to a new and useful tool-guide for cable-tool drills, more particularly to such a tool-guide which is removable from the line of drilling by automatic means when the drill-tool is retracted from the hole.

In a cable-tool drill a cable passes from a winch-drum on the main frame of the drill, around a heel-sheave at or near the front end of the machine, under a spudding-sheave mounted on the free end of a spudding-beam at or near the rear end of the machine, over a crown-sheave near the upper end of the mast at the rear of the machine, and downward into the hole which is being drilled into the ground.

At the lower end of this cable is a string of percussion drilling tools, terminating at a bit. The tools are reciprocating up and down by the reciprocating action of the spudding-sheave on the cable.

A tool-guide is normally constructed to be a cylindrical guide affixed to the mast of the drill to be located vertically over the center line of the hole while drilling. This position of the tool-guide and tool is the normal drilling position. The tool-guide serves to keep the tools vertical and so make the hole vertical, especially at the start of drilling. It also serves to prevent whipping of the cable.

When the tool is retracted from the hole for bailing, the tool and tool-guide must be removable from the line of drilling to permit the bailer to be lowered into the hole for bailing. This position of the tool and tool-guide, out of the line of drilling, is the bailing position.

In the past, tool-guides have consisted of one or two short tubular pieces to be swung to one side when not in use, or a longer longitudinally-divided tubular piece opening horizontally to permit extraction of the tool from its guide. The swinging and tool extracting action has been accomplished by hand-operated tool-guide retracting mechanism and the swinging of the tool out of the line of drilling has usually been done manually by swinging the drill-tool to one side of the hole, holding in that position, and lowering the tool to rest on the deck of the drill.

The short tubular guide encompasses only a small part of the length and stroke of the tool, so that upon reciprocation the tool may momentarily leave the guide and no longer be held to true vertical movement. That is, if such guides are mounted rather low there is, of course, no guide for the upper end of the tool at the start of a hole. If mounted rather high, the tool will be left unguided for considerable time as work progresses or until the major portion of the tool has entered the natural guide formed by the well. Guides may be improved by using a plurality of short tubes. This, however, adds to the complication of the operator as considerable time and effort is required in clamping each tube in position for drilling and loosening it in preparation for bailing. Also the addition of more of these parts adds to the effort required to move them sufficiently to make way for the bailer.

2

The longitudinally-divided tube is not a rigid guide, in that, after considerable reciprocating movement of the tool in the guide the tool slaps and bangs against the sides of the guide, thus tending to separate the two halves of the tubular guide. After the guide is thus loosened or spread, the tool is not held to true vertical movement; also in this type of guide, when it is retracted from around the tool and the tool is raised from the hole, said tool must still be swung to one side to use the bailer. 10 This swinging action of the tool has heretofore always been accomplished manually.

In the prior art, tool-guides have required the operator of the drill to make the following adjustments in retracting the drill for bailing: (1) He must unlatch the tool-guide, 15 (2) He must swing the tool-guide out of the line of drilling, (3) He must then swing the tools out of the line of drilling manually, which in heavy drills requires considerable effort on the part of the operator, (4) He must fasten the tool in a remote position, usually by holding 20 the tool over the desired remote position and then lowering it to the frame of the drill.

When the driller finishes bailing and desires to begin drilling again, the following movements are necessary before drilling can begin: (1) He must raise the tool off the 25 frame of the drill and allow it to swing into position, (2) He must swing the tool-guide back into its normal drilling position located vertically over the hole, and (3) He must latch the tool-guide.

A desirable feature for tool-guides, though not found 30 in the prior art, is a means whereby the tool-guide and tool may be automatically retracted from the line of drilling by action of the tool after raising it from the hole. This guide incorporates means for accomplishing this objective.

35 Accordingly the principal objects of this invention are: (1) To provide a long and rigid tool-guide which, when it is retracted, does not interfere with bailing or replacement of tools. (2) To provide such a tool-guide that it will be retractable by power means which is readily 40 available in the drill. (3) To provide a tool-guide to eliminate manual retraction of the tool from the line of drilling. (4) To provide a tool-guide that is retractable by potential energy of the tool when raised out of the hole and then lowerable. (5) To provide a tool-guide which is also retractable by power raising of the tool. 45 (6) To provide a tool-guide which retracts vertically as well as horizontally. (7) To provide a constraining means to attach the tool to the mast and allow the tool and the guide to move away from the line of drilling. (8) To provide a constraining means such that, when the tool is moved horizontally sideways from the line of drilling, the tool and guide may be cocked to give a cant effect, so that the force of the rope exerted by the 50 pull of the tool will pull from the center of the crown-sheave, so as not to cause the rope to become unthreaded from the sheave. (9) To provide a tool-guide which will absorb the shock from an upward blow by the tool against the lower end of the guide without harming its mounting on the drill. (10) To provide a tool-guide, 55 which when retracted will return to drilling position by potential energy available in the tool-guide and/or drill-tools and be controllable through the rope and the winch of the drill. (11) To provide a tool-guide which is compact, simple, and easy to retract. (12) To provide a tool-guide which requires a minimum of adjustment.

In addition to the principal objects, above stated, a number of novel and useful details have been worked out, which will be readily evident as the description progresses.

70 This invention consists in the novel parts and in the combination and arrangement thereof, which are defined

in the appended claims, and of which four species are exemplified in the accompanying drawings, hereinafter particularly described and explained.

Throughout the description in each of these variants the same reference number is applied to the same member or to similar members.

Figure 1 is a side elevation of a cable-tool drill showing the first variant of this invention.

Figure 2 is an enlarged view of a tool-guide similar to the one shown in Figure 1, eliminating the rope-pulley means for retracting the tool-guide and showing in its place a second means for retracting the tool-guide.

Figure 3 is a similarly-enlarged view of a tool-guide as shown in Figure 2. This figure shows still another means for retracting the tool-guide.

Figure 4 is a side elevation of a cable-tool drill showing a second constraining means for the tool-guide in this invention.

Figure 5 is an enlarged front view of Figure 4 taken along lines 5—5, omitting the drill-tool, bit, and hook.

Figure 6 is a side view of Figure 5, adding the drill-tool, bit, and hook.

Referring now to Figure 1, we see that 11 is the main frame of the drilling machine and 12 is the well-hole being drilled in the ground. 13 is any convenient form of ground support for the drill, preferably, but not necessarily, of the endless-tread variety.

Drill-tool 14 is suspended by a rope 15 to be raised or lowered through an opening 34 in the drill frame and into the hole 12. Rope 15 passes over a crown-sheave 16 at the top of mast 17, thence around spudding-sheave 18, on spudding-beam 19, thence around heel-sheave 20 at the rear pivot of beam 19, and thence to a winch-drum 21. The beam 19 is reciprocated by motor 22 acting through intermediate unnumbered belting and gearing and crank 23 of pitman 24. Various methods, well known in the art, can be used to pay-out and take-in rope 15.

The machine thus far described is conventional and, as to its details, constitutes no part of this invention.

Let us now turn to the tool-guide 24 and the means for retracting the guide 24 from the line of drilling. This is the essence of this invention and several variants are described to achieve this result.

In the variant of Figure 1, the tool-guide 24 is a one-piece tubular-guide mounted on the mast 17 (Figure 1) by lever arms 25. Lever arms 25 are U-shaped at one end so as to fit around the tool-guide 24 and be pin-connected by pins 26 to the sides thereof. The other end of said lever arms 25 extend horizontally from the mast 17 and are held from further rotation downward (counterclockwise) by a stop 28; said stop 28 as shown is an integral part of the mast 17 on the upper lever arm connection on the mast 17, but it is understood that it is not necessarily limited to the upper lever arm only. The lever arms 25 are free to rotate clockwise when the tool-guide is moved from the drilling position (solid outline) to the bailing position (dotted outline) in Figure 1.

A rope 29 is attached to the upper end of the tool-guide 24 at an eyelet 30 which is rigidly fastened to the tool-guide 24. The rope 29 extends over a sheave 31 suspended from mast 17 at a point above the top of tool-guide 24 when it is retracted to the bailing position (shown in dotted outline in Figure 1). From sheave 31 the rope 29 extends downward to a point where a hook 32 is attached to the rope 29 by tying it through an eyelet on the end of hook 32. The "hook end" of part 32 is fastenable to the bit 33 of drill-tool 14. Drill-tool 14 is threaded through tool-guide 24 and rope 15 is connected to the upper end of drill-tool 14 by a conventional connecting means.

As winch-drum 21 winds on rope 15, the drill-tool 14 is lifted from well-hole 12 until the drill-tool 14 is lifted into the tool-guide 24 to a position where hook 32 may be hooked onto drill-tool 14 at the bit 33. After the hook 32 engages the drill-tool 14, the operator lowers the

drill-tool 14 under the control of the winch, so that as the drill-tool 14 is lowered, the rope 29 is pulled downward and thus tool-guide 24 is swung vertically and to the right (Figure 1, dotted lines) about pins 27. Thus, the weight of the drill-tool retracts the tool and the tool-guide from the line of drilling automatically and with a minimum of operations on the part of the operator.

After bailing is completed and it is desired to realign the tool-guide 24 and drill-tool 14 with the well-hole 12 for drilling, the operator engages the clutch on the drill-winches and raises the drill-tool 14. In so doing, slack is created in rope 29 and the tool-guide lowers by its own weight into a normal drilling position in line with the well-hole 12. As the tool-guide 24 lowers (counterclockwise rotation about pin 27 in Figure 1) it carries drill-tool 14 to the left along with it. When tool-guide 24 is restored to its lowered position, the hook 32 may be removed from drill-tool 14. The operator disengages the winch-clutch to stop hoisting the drill-tool, and the drill-tool is lowered into the well-hole 12 under control of the winch-brake to resume drilling.

The length of rope 29 and hook 32 will determine the height above the drill-frame 11 to which the drill-tool 14 must be raised to engage hook 32 with drill-tool 14. The minimum working height to which the drill-tool 14 may be raised to engage hook 32 is limited to a distance between the bit 33 and the drill-frame 11 equal to the length of lever arm 25 measured between pin 27 and pin-connection 26.

In this variant of the invention, the power lowering of the drill-tool 14 is utilized to swing the tool-guide and drill-tools out of the line of drilling and hold them in this removed position, whereas in the prior art it was necessary to move the tools and guide by multiple manual operations and with a greater consumption of time and energy on the part of the operator. The power raising of the drill-tool is utilized to swing the tool-guide and drill-tools back into line with the well-hole 12, thus this invention requires a minimum of operations by the operator to realign the tool-guide for drilling.

Turning now to Figure 2, another variant of this invention is described for retracting the tool-guide and drill-tools from the line of drilling.

In describing this variant of Figure 2, only that portion of the structure which is changed from Figure 1 is mentioned.

Drill-tool 14 is connected to rope 15, the same as in Figure 1, and is threaded through a one-piece tubular tool-guide 24, said tool-guide being constructed so that it narrows to a collar 36 at its upper end. When it is desired to swing the tool-guide 24 and drill-tools 14 out of the line of drilling, the drill-tool 14 is hoisted by the power winch of the drill, to engage the top of the drill-tool 14 with the collar 36 of tool-guide 24 so that the shoulder 36' on the top of said tool will bear against collar 36. By continuing to hoist the drill-tool 14, the tool-guide 24 will be hoisted along with the drill-tool 14. Tool-guide 24 is connected to the mast by lever arms 25 in the same manner as described in Figure 1 hereof, so that as the tool-guide tends to move upward vertically, it also swings to the right (clockwise in Figure 2) about pins 27. As the tool-guide 24 swings upward and to the right, the drill-tool 14 is interlocked therewith and both of these parts 14 and 24 are removed from the line of drilling. When the tool-guide 24 and drill-tool 14 are removed to the retracted position (dotted outline in Figure 2) the operator ceases to hoist the drill-tool and sets the brake of the drill-winches, thus holding the tool in the desired position.

When bailing operations are finished and it is desired to realign the drill-tool 14 with the well-hole 12 for drilling, the operator merely lowers the drill-tool 14 by unspooling the drill-winches. In so doing, the drill-tool 14 and tool-guide 24 swing down and to the left (counterclockwise in Figure 2) until the uppermost lever arm 25 engages the

stop 28, whereupon the drill-tool 14 continues to lower into the well-hole 12 ready to resume drilling.

Now let us turn to Figure 3, which shows still another variant of this invention.

In Figure 3, the tool-guide 24 has its upper end open and unrestricted so that drill-tool 14 may extend up through the top of the tool-guide. Thus, when the drill-tool 14 is hoisted it will thread through the tool-guide 24 until the lower portion of the drill-tool 14 (which is the bit 33 and is of a larger diameter than the bottom opening of tool-guide 24), engages with the lower portion of the tool-guide and carries it along with the tools as they are hoisted further. From this point the tool-guide and drill-tool reacts in the same manner as previously described for Figure 2.

In lowering the tool-guide, the drill-tool is lowered, as previously described for Figure 2, and the drill-tool and tool-guide 24 drop back into alignment with the well-hole 12 under the influence of their own weight. The rate of descent of the tool and its guide is controlled by the winch-brake as the winch pays out line and lowers the drill-tool.

In Figures 4, 5 and 6, a second form of constraining means is shown, namely: a slotted constraining means, which has been substituted for the lever arms 25 as shown and described in Figures 1, 2, and 3. The same reference-numbers are used in describing Figures 4, 5, and 6 as were used in describing Figure 1, wherever the parts are the same.

In describing this invention as shown by Figure 4, 11 is the frame of a cable-tool drill with a hole 34 in the frame for the drill-tool 14 to be lowerable into the well-hole 12. The mast 36 has its inside (nearest the well) face more nearly vertical, whereas the mast 17 in Figure 1 is inclined toward the well. This is desirable in that much of the bracing and cross-beams, as shown in Figure 1, may be eliminated without sacrificing rigidity. However, by using such a mast, it is no longer practical to move the tool-guide 24 and drill-tool 14 toward the mast, because the clearance between the mast and the tool-guide has been decreased by an amount so that the clearance is insufficient to remove the tool-guide from the line of drilling. Therefore, in this variant, the tool-guide 24 is moved upward and to one side of the mast when the bailer is to be used. This is done by the following type constraining means:

Referring to Figures 5 and 6, mast-plates 37 and 37a are welded to the mast 36, so that it is rigidly secured thereto. The mast-plates 37 and 37a have slots 38 and 38a cut into them at inclined angles. The slots in the two mast-plates are cut at different angles, but slot 38 in mast-plate 37, or the uppermost mast-plate, will be inclined at a greater angle, measured from the horizontal, than slot 38a in mast-plate 37a, (the lowermost mast-plate). In Figure 5, the slot 38 in the upper mast-plate 37 is inclined at approximately 60 degrees to the horizontal and the slot 38a in the lower mast-plate 37a is inclined at approximately 45 degrees to the horizontal, but let it be understood that this invention is not to be limited to this combination of degrees of incline; only that the upper slot be at a steeper incline than the lower, or that they both be at the same incline.

The tool-guide 24, has two guide-plates 39 and 39a welded to its side, one near the top and the other near the bottom thereof. The upper guide-plate 39 has two holes bored through its face to receive two bolts 40 and 40a. The centers of these two holes are to lie along a line that is inclined to the horizontal to the same amount as slot 38 (in Figure 5, this incline is 60 degrees). The lower guide-plate 39a has two holes bored in its face to receive bolts 41 and 41a and the centers of these holes lie along a line that is inclined to the horizontal to the same amount as slot 38a (in Figure 5, this incline is 45 degrees). A spacer 42 has two holes through it matching the two holes in guide-plate 39 to receive bolts 40

and 40a. Bolts 40 and 40a are inserted through these holes in spacer 42, then through slot 38 and through the corresponding holes in guide plate 39 and fastened by nuts. The spacer 42 fits between the mast 36 and mast-plate 37 (Figure 6). The lower slide assembly is assembled by spacer 42a, (which is identical to 42) having bolts 41 and 41a inserted through the holes, through slot 38a, through the corresponding holes in guide-plate 39a and fastened by nuts in the same manner as described for 10 the upper slide assembly.

The tool-guide 24 has an eyelet 30 rigidly fastened thereto for connecting rope 29. The rope 29 passes over sheave 31 mounted above the tool-guide 24 on the mast 36. From sheave 31 the rope 29 extends downward to 15 a point where a hook 32 is attached to the rope 29 by tying it through an eyelet on the end of the hook 32. The "hook end" of part 32 is fastenable to the bit 33 of drill-tool 14.

In Figure 4, drill-tool 14 is threaded through the tool-guide 24 and rope 15 is connected to the upper end of drill-tool 14 by a conventional connecting means. As winch-drum 21 winds on rope 15, the drill-tool 14 is lifted from well-hole 12 until the drill-tool 14 is lifted into 20 the tool-guide 24 to a position where hook 32 may be hooked onto drill-tool 14 at the bit 33. After the hook 32 engages the drill-tool 14, the operator lowers the drill-tool 14 under the control of the power-winch, so that as the drill-tool 14 is lowered, the rope 29 is pulled downward and thus tool-guide 24 is lifted upward and to the right (Figure 5) constrained by slots 38 and 38a of mast-plates 37 and 37a. Thus, the weight of the drill-tool 25 retracts the tool and the tool-guide from the line of drilling automatically and with a minimum of operations on 30 the part of the operator.

More particularly, the slide assemblies constrain the movement of the tool-guide 24 as follows:

When the tool-guide 24 is in the normal drilling position, the lower bolt 40a bears against the bottom of slot 38 and bolt 41a bears against the bottom of slot 38a, to hold the tool-guide in the lowered position for drilling. As force is applied through rope 29 to lift the tool-guide, the bolts 40, 40a, 41 and 41a slide along their respective inclined slots 38 and 38a to carry the tool-guide sideways along the course of these inclined 45 slots as it is lifted upwards. Due to the fact that the slope of the incline in slot 38 is greater than the slope of the incline in slot 38a, the horizontal travel of the top of the tool-guide will be somewhat less than the horizontal travel of the bottom of the tool-guide.

50 This will result in the tool-guide assuming a slanted position, which may more appropriately be described as a cant effect. The cant effect is desirable for three reasons: (1) Due to the fact that the lower bell of the tool-guide is of a larger diameter than the upper diameter of 55 the guide, it is desirable to retract the lower portion of the tool-guide further horizontally away from the well than the top portion. (2) The cant effect decreases the tendency of the main rope 15 to jump the sheave, due to the fact that the tool-guide slants towards the center-line of the sheave when the tool is in the retracted position. (3) The cant effect of the tool makes it tend 60 to swing like a pendulum while it is in the retracted position. Thus, the tool and tool-guide are allowed to return more smoothly from the retracted position.

65 After bailing is completed and it is desired to realign the tool-guide 24 and drill-tool 14 with the hole 12 for drilling, the operator engages the clutch on the drill-winches and raises the drill-tool 14. In so doing, slack is created in rope 29 and the tool-guide lowers by its own 70 weight along the inclined slots 38 and 38a until bolt 40a and bolt 41a bear against the bottom of slots 38 and 38a respectively. This is the normal drilling position and the tool-guide and tools are again lined up with the well-hole 12. When the tool-guide 24 is restored to its low-

ered position, the hook 32 may be removed from drill-tool 14. The operator then disengages the winch clutch to stop hoisting the drill-tool, and the tool is lowered into the well-hole 12 under the control of the winch-brake.

The length of rope 29 and hook 32 will determine the height above the drill-frame 11 to which the drill-tool 14 must be raised to engage hook 32 with drill-tool 14. The minimum working height to which the drill-tool 14 may be raised to engage hook 32 is limited to a distance between the bit 33 and the drill-frame 11 equal to the length of slot 38 minus the distance between bolts 40 and 40a.

The slotted constraining means shown in Figures 4, 5, and 6, could equally well be substituted for the hinged constraining means of the variant of Figure 2 or the variant of Figure 3.

To summarize. It will be seen that the variants herein described employ three alternative means of using vertical motion of the drilling tool to raise the tool-guide, and two alternative means for constraining the thus-caused upward motion of the tool-guide to move it and the tool away from a position above the hole which is being drilled.

The means whereby the tool-guide is automatically retracted from alignment with the line of drilling and then returned automatically into alignment with the line of drilling may be generically described to operate as follows:

A tubular tool-guide is movable upward and away from the line of drilling, and the direction and amount of movement is controlled by a constraining means. Moving the drill-tool vertically to engage or disengage with the tool-guide will actuate this movement of the tool and tool-guide away from the line of drilling. Said movements of the tool-guide and drill-tools are achieved automatically by vertical motion of the drill-tool under the influence of the winch through the rope. Movement of the tool-guide and tool to realign same with the well-hole is achieved automatically by the potential energy of said parts, with their rate of movement back to a normal drilling position from the retracted position controllable by the winch.

The above generically-described structure and operations are common to all species of this invention.

Having now disclosed six forms of this invention, it is to be understood that this invention is not to be limited to the specific form or arrangement of parts herein described and shown.

We claim:

1. In a cable-tool drill which comprises a mast, a sheave journaled in an elevated position on the mast, a cable-tool, a winch, a hoist-rope passing from the winch over the sheave and operatively connected to the tool to raise and lower the tool, and an integral elongated tool-guide movably connected to the tool, the combination of means mounting the tool-guide to the mast for vertical and lateral bodily movement thereof relative to the mast; and interlock means supported on the mast, movable relative thereto and having a portion thereof connected to the tool-guide, said interlock means having another portion thereof adapted to be connected to the tool, whereby the interlock means is movable under the weight of the tool as it moves downwardly to lift the tool-guide and thereby move said guide and said tool out of the line of drilling to a position adjacent the mast.

2. A cable-tool drill according to claim 1, further characterized by the fact that the interlock means comprises; a hook adapted to be connected to the tool; a second sheave; means for connecting this sheave to the mast; and a rope connected at one end to the tool-guide, operatively

connected to the sheave, and connected at the other end to the hook.

3. A cable-tool drill according to claim 2, still further characterized by the fact that the means mounting the tool-guide to the mast comprises: at least one lever arm; means for pivotally connecting said arm at one of its ends to the tool-guide and its other ends to the mast; and a stop means connected to the mast, so that when the tool-guide is in its normal drilling position said stop means bears against the lever arm to hold the tool-guide in position.

4. A cable-tool drill according to claim 2, further characterized by the fact that the means mounting the tool-guide to the mast comprises: multiple mast-plates rigidly connected to the mast, said plates having slots therein that are inclined to the horizontal; multiple guide-plates rigidly connected to the tool-guide spaced longitudinally along one side thereof; multiple bolts adapted to be fitted through the slots in the mast-plates and bolted to the guide-plates, so that when the tool-guide is in the drilling position the bolts bear against the lower point in the inclined slot, and the bolts are free to slide in the slots to allow the tool-guide to move upward and away from the line of drilling as the tool-guide is lifted under the weight of the tool.

5. A cable-tool drill according to claim 4, still further characterized by the fact that the slot in the upper mast-plate has a greater horizontal incline than the slot in the lower mast-plate, to allow the lower portion of the tool-guide to move to a position further away from the line of drilling than the top portion of the tool-guide, and cant the tool-guide and tool at a position of rest.

6. A cable-tool drill according to claim 1, further characterized by the fact that the cable-tool comprises a drill bit having a larger cross-sectional area than the cross-sectional area of the tool-guide; means for connecting the bit to the lower end of the tool whereby the vertical upward movement of the tool through the tool-guide under the influence of the winch through the rope will engage the bit with the lower end of the tool-guide and move the tool and the tool-guide out of the line of drilling to a position of rest; and still further characterized by the fact that the means mounting the tool-guide to the mast comprises: multiple mast-plates rigidly connected to the mast, said plates having slots therein that are inclined to the horizontal; multiple guide-plates rigidly connected to the tool-guide spaced longitudinally along one side thereof; multiple bolts, to be fitted through the slot in the mast-plate and bolted to the guide-plates, so that when the tool-guide is in the drilling position the bolts bear against the lower point in the inclined slots and the bolts are free to slide in the slots to allow the tool-guide to move upward and away from the line of drilling.

7. A cable-tool drill according to claim 6, still further characterized by the fact that the slot in the upper mast-plate is of a greater horizontal incline than the slot in the lower mast-plate, so as to allow the lower portion of the tool-guide to move to a position further away horizontally from the line of drilling than the top portion of the tool-guide and give the tool-guide and tool a cant effect at a position of rest.
